(57) **CLAIM**

The ornamental design for a magazine pouch, as shown and described.

DESCRIPTION

FIG. 1 is a perspective view of a magazine pouch.
FIG. 2 is a side elevation view of a magazine pouch.
FIG. 3 is a opposite side elevation view of a magazine pouch.
FIG. 4 is a top plan view of the view of a magazine pouch.
FIG. 5 is a bottom plan view of a magazine pouch.
FIG. 6 is a front elevation view of a magazine pouch; in this view the broken lines of the magazine are for illustrative purposes only and form no part of the claimed design; and,
FIG. 7 is a rear elevation view of a magazine pouch.
